UNITED STATES PATENT OFFICE.

HENRY THOMAS, OF EAST HAM, ENGLAND.

HOLDER FOR TAPS, REAMERS, DIES, OR THE LIKE.

Application filed January 22, 1920. Serial No. 353,331.

(GRANTED UNDER THE PROVISIONS OF THE ACT OF MARCH 3, 1921, 41 STAT. L., 1313.)

To all whom it may concern:

Be it known that I, HENRY THOMAS, a subject to the King of England, residing at 144 Clements Road, East Ham, in the county 5 of Essex, England, have invented certain new and useful Improvements in Holders for Taps, Reamers, Dies, or the like, (for which I have filed application in England January 20, 1919, Patent No. 127,528 of 10 1919), of which the following is a specification.

This invention has for its object the provision of a device of the class named which shall be of improved construction and operation.

15 The invention is exemplified in the combination and arrangement of parts shown in the accompanying drawings and described in the following specification and it is more 20 particularly pointed out in the appended claims.

In the drawings:—

Fig. 1 is a plan view of one form of the device.

25 Fig. 2 is a similar view to Fig. 1 partly in section.

Fig. 3 is an underside plan view of the same device.

30 Fig. 4 is a view in cross section at line 4—4 of Fig. 1.

Fig. 5 is a perspective view of the rotary member.

Fig. 6 is a fragmentary view of another form of the device.

35 Fig. 7 is a similar view to Fig. 6, but in section.

Fig. 8 is an underside plan view of the device shown in Fig. 6.

40 Fig. 9 is a view in cross section at line 9—9 of Fig. 6.

Fig. 10 is a view in perspective of the rotary member employed in this construction.

45 Figs. 11 and 12 are views in plan and side elevation respectively of a modified form of tool, which can be used with the device illustrated in Figs. 6—10.

Fig. 13 is a fragmentary longitudinal section taken on Fig. 1 at right angles to the section shown in Fig. 4; and

50 Fig. 14 is a fragmentary longitudinal section taken on Fig. 6 at right angles to the section shown in Fig. 9.

In the construction illustrated in Figs.

1—5 the device comprises a pair of handle portions 1, 1 having a central boss 55 portion 2. The boss portion 2 is provided with a circular recess 3 having a central projecting boss 4 and a right angle V shaped notch 5.

Within the recess 3 is placed the rotary 60 member 6, which is provided with four right angle V shaped notches 7, 8, 9, and 10 of various sizes. The member 6 is provided with a central hole 11 adapted to fit over the boss 4 and it is further provided with a projecting portion 12 in order to facilitate turning it round on the boss 4.

65 The parts are assembled as shown in the drawings, with any one of the notches 7, 8, 9, or 10 opposite to notch 5. When the desired notch has been moved into position the central member 6 can be held stationary by the set screw 13, which screws into the boss 4.

70 The shank of the tap or like tool enters the square recess formed by the co-operation of two notches as shown clearly by Fig. 2. In order that the shank of the tap or like tool shall not foul the set screw 13 the holder is placed on the tap, so that the tap projects from the opposite side to the set screw 13. 75 In order to allow a square and even shoulder on the holder for making contact with the shoulder on the tap, the underside of the boss portion 2 is recessed as shown at 14 in Fig. 3, which serves to bring the face of the holder at this point level with the underside of the rotary member 6.

80 Referring to Figs. 6—12 the object of this modified construction is to provide a holder for taps or the like suitable for various sizes of taps and at the same time capable of holding a screw cutting plate such as is shown in Figs. 11 and 12.

85 In order to make this possible it is necessary to dispense with the central boss 4 and 90 to provide instead a central hole 15 leaving a flange 16 around the central recess 3.

95 In this construction the rotary member has no central hole 11 as shown in Fig. 5, but is formed with a circumferential V shaped 100 groove 17 as shown in Fig. 10.

105 In this construction also the notch 5 in the recess 3 may be made as shown in the drawing, that is, it does not extend completely through the thickness of the boss 2, but extends only as far as the flange 16.

In this construction the parts are assembled as before, the projecting portion 12 on the rotary member 6 forming a convenient means for rotating said member when required. The rotary member 6, however, is held in position by one or more radial set screws 18 (three are shown). These set screws 18 are shaped at their ends as shown at 19 to enter the groove 17.

10 In the construction shown in Figs. 6-10 a threaded hole 20 may be provided to accommodate the set screw 18; when a rotary member such as shown in Fig. 5 is used with a holder as shown in Figs. 6-10.

15 It will be seen that the construction shown in Figs. 6-10 can conveniently be used with a screw plate such as shown in Figs. 11 and 12, and such a screw plate may be provided with grooves as shown at 21.

20 I claim:

1. A holder for tools comprising a boss member and a member fitted therein and movable relative thereto, said boss member having a fixed notch therein and said movable member having a plurality of notches of different sizes, the arrangement being such that said movable member may be moved into one of a number of positions with a fixed notch in the boss member opposite to one of the notches in the movable member so as to enable the notches to fit over the shank of the tool with the faces of the fixed notch in said boss member engaging said tool, and means for retaining said movable member in its adjusted positions.

2. A tool holder comprising a member having an opening therein, a second member fitted in said opening and movable relative to said first member, said first member having a V shaped notch therein the sides of which form fixed tool-engaging surfaces while said movable member has a plurality of V shaped notches of different sizes arranged to be moved selectively into registration with the notch in said first named member to form tool sockets of various sizes.

3. A tool holder comprising a pair of members movable relative to one another, one of said members having a notch therein while the other of said members has a plurality of notches of different sizes to be brought selectively into registration with the notches in said first named member to provide tool sockets of various sizes and means for holding said movable member in fixed position relative to said first named member with any one of the notches of said

movable member in registration with the notch of said first named member.

4. A tool holder comprising a handle 60 member, a movable member fitted in an opening in said handle member, said members having notches therein arranged to be brought into registration with one another to provide a tool socket and means for holding said members in position relative to one another, said handle member being recessed to provide a surface thereon which is flushed with a surface on said movable member.

5. A tool holder comprising a handle 70 member having an opening therein, a movable member fitted in said opening, said members having notches arranged to be brought into registration with one another to provide sockets of various sizes, said movable member having a grooved periphery and means threaded in said handle member for engaging the grooved periphery of said movable member to hold said movable member in fixed position in said handle member. 80

6. A tool holder comprising a handle member having an opening therein and a movable member fitted in said opening, said members having notches arranged to be brought into registration with one another 85 to provide sockets of various sizes and means on said movable member to facilitate adjustment thereof to bring said notches into registration with one another.

7. A tool holder comprising a handle 90 member having a cylindrical opening therein, a cylindrical plug rotatably fitted in said opening, said handle member having a notch therein communicating with said cylindrical opening, said cylindrical plug having a plurality of notches of different sizes in the periphery thereof, arranged to be brought into registration with the notch in said handle member to provide sockets of various sizes means on said cylindrical plug by 95 which it may be rotated to bring the various notches therein into registration with the notch in said handle member and means for holding said cylindrical plug in adjusted positions, said handle member having a recessed portion to provide a surface in a plane with the surface of one end of said cylindrical plug, adjacent registering notches of said members.

In testimony whereof I have signed my 110 name to this specification on this 30th day of December, A. D. 1919.

HENRY THOMAS.
